UNITED STATES PATENT OFFICE.

CURTIS L. CRUVER, OF CHICAGO, ILLINOIS.

SOUNDING TOY.

1,110,114.

Specification of Letters Patent. Patented Sept. 8, 1914.

Application filed December 26, 1912. Serial No. 738,523.

To all whom it may concern:

Be it known that I, CURTIS L. CRUVER, a citizen of the United States, residing at Chicago, in the county of Cook and State 5 of Illinois, have invented certain new and useful Improvements in Sounding Toys, of which the following is a specification.

The object of this invention is to produce a toy of novel construction which will issue 10 a whistling sound resembling the call of a bird.

In the accompanying drawings, Figure 1 is an elevation of a toy embodying the features of my invention, showing the manner 15 of holding and operating the toy. Fig. 2 is an enlarged longitudinal central sectional view. Fig. 3 is a transverse section on line 3 3 of Fig. 2, and Fig. 4 is a section on line 4 4 of Fig. 2.

20 The toy comprises a hollow cylinder 5 having a slot 6 running from end to end thereof. The cylinder 5 may be formed from a flat piece of sheet metal rolled into the form of a tube, the adjacent meeting 25 edges being spaced apart a suitable distance to form a slot 6.

One end of the cylinder is closed by a cap 7 which may be of sheet metal and may be secured to the cylinder by any common or 30 preferred form of seam 8. An opening 9 may be provided centrally of the cap 7.

The opposite end of the cylinder 5 is closed by a head 10 of relatively great thickness. In the outer side of this head is 35 formed a recess 11, and a guide opening 12 leads from the bottom of said recess to the inner side of the head. The head may be conveniently secured in place by a staple 10^a bridging the slot 6 in the cylinder and entering 40 said head.

A device 13 is mounted at the outer side of the head 10, said device comprising a disk 14 having a semi-spherical boss 15 at its inner side, and further having a handle 45 16 at its outer side. The handle 16 may be given the general shape of a bird, as indicated in Fig. 2, if desired. The device 13 may be conveniently made of an integral piece of metal. Said device is connected to 50 the head in the present instance by means of an attaching member or stem 17 which may be in the form of an ordinary nail, the

point end of the nail being secured in a bore 18 in the boss 15. Said nail extends through the guide opening 12 in the head 55 10, and the head of the nail overlies the inner end of said opening 12 to prevent withdrawal of the nail from said opening.

In use, the handle 16 is grasped in one hand, and the opposite end of the cylinder 5 60 in the other, and said parts are given a relative rotary or twisting movement with the boss 15 in light frictional contact with the mouth of the recess 11. Owing to this friction between the parts, a whistling sound 65 will be issued, resembling somewhat the call of a bird. This sound is augmented and intensified by the cylinder 5, so as to be very clearly audible.

In the preferred form of my invention, I 70 construct the head 10 of wood, and the device 13, including the boss 15, of metal, but it is not absolutely essential that these materials be used.

Other minor changes within the scope of 75 the claims may also be made without departing from the spirit of my invention.

I claim as my invention:

1. A sounding toy comprising a cylinder having a longitudinal slot therein, a cap 80 closing one end of said cylinder, a head closing the other end of said cylinder, said head having a recess in its outer side, an operating device positioned adjacent to the outer side of said head, and comprising a 85 circular boss projecting into said recess and being adapted to be rotated in light frictional engagement with the walls thereof to create a whistling sound, a handle rigid with said boss for turning the latter, and a 90 pin adapted to form a loose rotatable connection between said boss and said head.

2. A sounding toy comprising a piece of sheet metal rolled to form a cylinder, the meeting edges of the metal being spaced 95 apart to form a slot extending from end to end of the cylinder, a sheet metal cap fixed to and closing one end of the cylinder, a wooden head fitting into the opposite end of the cylinder, a staple bridging said slot 100 and driven into said head for securing the latter in place, said head having a recess in its outer face and having a guide opening extending from the bottom of said recess to

the inner side of said head, a device to co-operate with said head comprising a stem movably mounted in said guide opening and having an enlargement at its inner end, a 5 semi-spherical boss fixed to the outer end of said stem and projecting into the outer end of said recess, and a handle fixed to said boss for rotating said boss in frictional

engagement with the walls of said recess to produce a sound. 10

In testimony whereof I affix my signature in the presence of two witnesses.

CURTIS L. CRUVER.
